UNITED STATES PATENT OFFICE.

SAMUEL R. ALLEN AND JAMES W. BAUGHMAN, OF DEWEY, OKLAHOMA; SAID BAUGHMAN ASSIGNOR TO SAID ALLEN.

FOUNTAIN-BRUSH.

1,115,370.

Specification of Letters Patent. Patented Oct. 27, 1914.

Application filed February 10, 1914. Serial No. 817,872.

To all whom it may concern:

Be it known that we, SAMUEL R. ALLEN and JAMES W. BAUGHMAN, citizens of the United States, residing at Dewey, in the 5 county of Washington and State of Oklahoma, have invented new and useful Improvements in Fountain-Brushes, of which the following is a specification.

This invention relates to fountain brushes 10 and more particularly to devices for applying shoe polish, stenciling liquid and the like.

An object of the invention is to provide a device having novel means for regulating 15 the amount of liquid discharged from the container which is determined by pressure upon an applying device, which applying device is moved toward or into juxtaposition with the dispensing tube as the liquid is discharged therethrough from the container.

Further objects of the invention will appear as the following description is read in connection with the accompanying drawing, which forms a part of this application, and 25 in which the figure is a vertical sectional view taken through the container and dispensing device.

Referring more particularly to the drawing, 1 represents a container of any suitable 30 character which is provided on its upper end with threads 2 and screwed thereon is a frusto-conical sleeve 3. The upper end of the container has an annular inwardly turned flange 4 against which a stopper 5 is 35 adapted to seat. This stopper is fitted within and carried by the sleeve 3, and, as shown, has the central aperture in which a tube 6 is mounted. The lower end of the tube has an inwardly turned flange 7 which 40 forms a seat for the valve 8 and an abutment for the spiral spring 9. Passing through the tube, and connected at one end to the valve is a plunger 10 to the opposite end of which is secured a head 11 having a plurality of ports 12 to permit the passage of the liquid from the container. This head carries a suitable applying device 13 in the 45 form of a brush or other body adapted to hold and dispense liquid, such as a sponge, as will be readily understood. The brush or 50 other body 13 projects through the outer end of the sleeve and fits the same closely so as

to prevent escape of liquid around the sides thereof. The lower end of the stem or plunger 10 which passes through the valve 8 55 is threaded so as to receive an adjusting nut 14 by which the tension of the spring may be regulated. The opposite end of the spring may seat against the head 11 or against a collar 15 secured upon the outer 60 end of the plunger 10, as shown.

Pressure upon the applying device 11 will cause the valve to unseat and allow the liquid in the container 1 to pass through the tube and apertures 12 onto the applying device. Upon release of the pressure on the applying device the spring will automatically close the valve and cut off the flow of liquid to the applying device.

It will be noted that all of the mechanism 70 is carried by the cork or stopper 5 and that this element may be readily removed from the sleeve after the sleeve has been disconnected from the container.

What is claimed is:—

1. In a liquid dispensing and applying device, a container, a stopper seated on the container and having a central aperture, a tube fitted in the aperture and projecting beyond the stopper, an abutment formed in 80 the tube, a plunger slidably mounted in the tube and having a valve at one end arranged to close the aperture, an absorbent member connected to the opposite end of the plunger, a spiral spring arranged between the absorb- 85 ent member and the abutment and means to hold the stopper on the container.

2. A dispensing and applying device comprising a container, a stopper arranged on the container and having an aperture, a 90 plunger operating within the stopper and carrying an absorbent applying device, a valve for closing the aperture which is released upon movement of the applying device toward the stopper and apertured means 95 removably mounted on the container for holding the stopper.

In testimony whereof we affix our signatures in presence of two witnesses.

SAMUEL R. ALLEN.

JAMES W. BAUGHMAN.
